UNITED STATES PATENT OFFICE.

FRANCIS W. ROBINSON, OF RICHMOND, INDIANA, ASSIGNOR TO ROBINSON & CO., OF SAME PLACE.

THRASHING-MACHINE AND STACKER ATTACHMENT THEREFOR.

SPECIFICATION forming part of Letters Patent No. 532,428, dated January 8, 1895.

Application filed May 24, 1893. Serial No. 475,362. (No model.)

To all whom it may concern:

Be it known that I, FRANCIS W. ROBINSON, of Richmond, Wayne county, Indiana, have invented certain new and useful Improvements in Thrashing-Machines and Stackers Attachments Therefor, of which the following is a specification.

This invention pertains to improvements in that class of thrashers having, incorporated with them, air blast tube stackers. In this class of thrashers, the thrasher itself has been provided with a tail chamber to receive the straw, the stacker tube rising from this chamber and the straw being forced out of the chamber and into the stacker tube by the fan within the chamber. In former practice in these compound machines the thrasher has been specially designed with reference to the stacker, the tail chamber forming a permanent tailward extension of the general thrashing structure. The principle of construction was such that the stacker required to be contemplated in the fundamental thrasher, and, if it was desired that a stacker should be provided for while not at once applied, a very material modification and increased expense was involved in the thrasher. Under that system it would be impossible to make the thrasher without the stacker but provided to receive it, without adding very much to the expense of the thrasher. The rear wheels of the thrasher were located below the tail-chamber which pertained to the stacker; but air-blast tube stackers have been arranged upon a system different from the compound or incorporated system above referred to. The stacker tube, with its base chamber to receive the straw, has been constructed as a complete independent machine and mounted on wheels so that it could be transported by means of a team. When this stacker was to be used, it was to be wheeled up to the tail of the thrasher so that the thrasher might tail its straw into the receiving chamber of the stacker. The only connection between the thrasher and the stacker consisted of a belt from which one of the thrasher shafts gave motion to the stacker mechanism. Such arrangement of stacker and thrasher did not form a combined machine, but formed sim-

ply two associated or aggregated machines, brought into convenient position with reference to each other for use at the same time; and when the machines were being transported there was no community of interest 55 whatever between them. The disadvantages of these separate machines are obvious, and are such as to have rendered them impracticable, and the universal custom has been to embody the principle of combination as first 60 above referred to, that is to say, such a special construction of the thrasher that it would form a part of the stacker.

In either of the two types above referred to, the wheels were placed under the stacker 65 chamber, such wheels being either the rear wheels of the thrasher in the one case, or, in the other case, the special wheels of the separate stacker.

By my improved construction, the thrasher, 70 fitted to receive the stacker at any time in the future, calls for no increased expense or complication in the structure. The stacker, when provided in the future, can be readily attached to the thrasher by common laborers, 75 and the construction of parts incident to the stacker is much simpler and much less expensive than usual.

In my construction the rear wheels of the thrasher are placed entirely forward of the 80 plane of the juncture between the thrasher and stacker and still these wheels become the wheels of the stacker when a stacker is provided. The thrasher is entirely complete without the stacker, which is merely an attachment that can be applied to and removed from the thrasher at will; but when the stacker at any time is added, it becomes to all intents and purposes one structure with the thrasher for the time being, attached thereto, and utilizing the thrasher frame and thrasher wheels and thrasher team as the means for its transportation—and this I believe to be broadly new with me.

When the combined structure is being 95 transported the stacker tube is turned forwardly over and in line with the thrasher so that the additional weight due to it is fairly balanced upon the rear wheels of the thrasher.

My improvements will be readily under- 100

stood from the following description, taken in connection with the accompanying drawings, in which—

Figure 1 is a side elevation of the rear portion of a thrasher provided with a stacker, of the class in question, and illustrating my invention. Fig. 2 is a similar view of the rear portion of the thrasher with the stacker removed. Fig. 3 is a similar view of the stacker portion removed from the thrasher; and Fig. 4 is a vertical longitudinal section of the tail chamber, separated from the thrasher and from the stacker tube.

In the drawings:—1 indicates the body portion of an ordinary thrasher and separator; 2, the rear wheels thereof, with their axle near the extreme rear of the thrasher-frame; 3, vertical end frames of the thrasher at the extreme rear of the thrasher; 4, the usual stacker tube; 5, the usual swiveling base of the stacker tube; 6, a base chamber on which the swiveling base of the stacker tube is mounted; 7, the stacker fan, disposed in the base of this chamber; 8, vertical frame timbers at the front of chamber structure 6 and adapted to set with their front faces against the rear faces of the frame timbers 3 of the thrasher, the lower ends of timbers 8 resting upon rearward projections of the sills of the thrasher; 9, bolts clamping the upper portions of timbers 8 and 3 firmly together; 10, bolts clamping the lower portions of those timbers together; 11, the main sills of the thrasher, projecting rearwardly beyond timbers 8 sufficiently to receive the bases of timbers 8; 12, the top seat of chamber 6 to receive the swiveling base 5 of the stacker tube; 13, carrier within the chamber 6 to receive the straw from the thrasher and carry it rearward under the base of the stacker tube within the influence of the stacker fan; and 14, cast brackets secured to the framing of chamber 6 and of the thrasher to receive the bolts 9.

From an inspection of Fig. 2 it will be obvious that the tail of the thrasher, instead of being complicated for stacker purposes, is more simple than in the case of ordinary thrashers, and by inspecting Fig. 3 it will be seen that the tail chamber construction for the thrasher is of peculiarly simple and efficient construction.

It will be obvious that thrasher framing constructed as in Fig. 2 adds no expense whatever to the thrasher on account of its adaptation to receive a stacker in the future. The stacker is applied to the thrasher by setting chamber construction 6 against the rear of the thrasher, with timbers 8 against timbers 3 and resting on the thrasher sills, after which bolts 9 and 10 are applied, completing the structure.

The chamber structure is supported wholly by the thrasher body and its wheels, the latter providing the support for the combined structure. The stacker tube may be turned into horizontal line forwardly over the thrasher so as to fairly balance its weight upon the rear wheels of the thrasher when the combined structure is being moved from place to place.

Having thus described my invention, what I claim as new, and desire to secure by Letters Patent, is—

The combination, substantially as set forth, of a thrasher-body having vertical frame timbers at its rear, a rear wheel axle under said body near said vertical frame timbers, a chamber structure provided with front frame timbers, a stacker-tube mounted upon said chamber structure, and clamps uniting the frame timbers of said chamber-structure to the frame timbers of said thrasher-body.

FRANCIS W. ROBINSON.
